UNITED STATES PATENT OFFICE.

ANDY KRONER, OF MONESSEN, PENNSYLVANIA.

FOLDING CRATE.

1,238,025.

Specification of Letters Patent. Patented Aug. 21, 1917.

Application filed September 30, 1916. Serial No. 123,134.

To all whom it may concern:

Be it known that I, ANDY KRONER, a citizen of the United States, residing at Monessen, in the county of Westmoreland and State of Pennsylvania, have invented new and useful Improvements in Folding Crates, of which the following is a specification.

This invention relates to folding crates.

The object of the invention is to provide a crate for shipping purposes, by means of which goods may be shipped and the crate returned in a knocked down or folded position.

Another object is to provide means for retaining the different parts of the crate in position as they are folded, in order to facilitate this operation.

A still further object is to provide a durable and inexpensive crate, which may be used for the shipment of poultry, vegetables or other merchandise.

In the drawings;

Figure 1 is a perspective view of the folding crate constructed in accordance with the present invention, shown in its set up position;

Fig. 2 is a longitudinal sectional view of the same taken on a line through the sliding hinges;

Fig. 3 is a similar view showing one of the end members in a raised or folded position, illustrating the manner in which the hinge retains this member in position;

Fig. 4 is a perspective view of the crate folded;

Fig. 5 is a detailed sectional view taken longitudinally through the slot plate carried by the bottom of the crate, and the hinge member carried by the side, showing the same in position occupied when the crate is set up, and also showing by dotted lines the position of the same when the crate is folded;

Fig. 6 is a sectional view through the lock employed for holding the crate set up.

Fig. 7 is a fragmentary elevation illustrating one of the hook and eye connections between the bottom and one of the side sections; and

Fig. 8 is a similar view showing the position of one of the eyes for engagement with the hook when the crate is in its folded position.

Referring to the drawings wherein like characters of reference denote correspond-

ing parts, the bottom of the crate is shown at 1. This bottom is preferably solid and has secured thereto along its end edges metal plates 2. These plates are formed with a longitudinal groove 3 within which a headed pin 4 is adapted to slide, the said pin being carried by one of the sides 5 of the crate. Angular plates 6 having slots 7 are secured to the side 5, the said side being formed with a socket 8 for the reception of the headed pin 4 which projects through the slot. The inner end of the slot 3 in the plate 2 is provided with an enlargement 9 by means of which the headed pin 4 can be removed from the slot to enable the bottom 10 and side 5 to be separated. The side is formed with an opening 11, which is closed by a suitable wire grating 12, this construction however if desired may be replaced by a panel in order to meet certain 15 conditions.

The top of the crate 13 is provided with a wire grating 14 and has secured to it short downwardly extending side sections 15 for use in folding the crate, as will appear 20 later on.

Each of the sections 15 is provided with headed pins 16, which work in slots 17 formed in the angular plates 18 carried by the side section 5, and the opposite side section 19. The construction just described provides for slidably hinging the side sections 5 and 19 to the top, for a purpose presently apparent.

The top 13 carries headed studs 20 for engagement with slots 21 in the angular plates 22 carried by each of the end members 23.

A pivoted hook 24 is provided within a socket 25 of the bottom, and is adapted to engage an opening 26 formed in the plate 27 95 secured to the edge of the side section 19. A ring 28 is secured to the pivot of the hook 24 to provide means for its operation.

Secured along the edges of the bottom, are end plates 29 which act as a guide for the 100 side member 5 during the folding or setting up operation. A hook 30 pivoted upon one side of the bottom 1 is adapted for engagement with an eye 31 carried by the side section 19, when the crate is in a set up position. A similar hook 32 is pivoted upon the opposite side of the bottom 1 and engages an eye 33 upon the front section 5. Studs 34 carried by the ends of the crate, are so positioned as to engage sockets 35 formed in the 105 110

plates 2 when the crate is set up. A similar stud 36 carried by the side section 19 is adapted to engage the socket 37 in the bottom 1.

5 When it is desired to fold the crate, the section 19 is first released by operating the hook 24 and the two end sections are folded upward against the under side of the top, the pins 34 being first disengaged from the openings in the plates 2 by lifting the said end sections. The headed pins sliding within the slots in the angular plates prevent the ends from dropping downward. The side section 19 and the ends are shoved in a direction away from the hook 24. The side section 5 and the end sections will then be neatly folded together, it being necessary to then fold the side section 19 upward against the ends of the crate. By pulling these 15 folded members back in the direction of the hook, the studs carried by the short side sections 15 are caused to slide in their respective angular slots and lock the sections 5 and 19 against the ends. The folded sections are 20 then pulled over until they are directly above the bottom 1, the studs of the headed pins sliding in the slots in the plate 2 for this purpose. The hooks pivoted to the side edges of the bottom 1 are then engaged in 25 the eyes of the top element and the crate is then securely formed in its collapsed or folded position.

It will be seen from the foregoing description when taken in connection with the accompanying drawings, that the invention 30 provides a simple and durable folding crate, constructed in such a way as to aid in the operation of folding.

35

Having described the invention what I claim, is;

1. A crate comprising bottom, top, side and end sections, connections whereby the end sections may be folded upward and held against the top section, connections whereby one of the side sections may be folded and held against the said end sections, means connecting one of the side sections with the bottom section to permit of the folding of the top, side and end sections over the bottom section and means for locking the said sections in folded position. 40 45

2. A folding crate comprising a bottom, top, sides and ends hinged and slidably connected together, said hinges and sliding connections consisting of slotted plates having pivot pins slidable therein. 50 55

3. A folding crate comprising bottom, top, side and end sections, slotted plates secured to said bottom section, pivot pins carried by one of the side sections and slidable in said slotted plates, sliding hinges for connecting the other side, top and end sections, pins carried by the end sections for engagement with sockets provided in the bottom section and means located within one wall of the 60 65 crate and operable from the exterior thereof for locking the crate in its set up position.

4. A folding crate comprising a bottom, top and sides slidably connected together, means included in the connecting means for holding the crate in its folded position and guide plates carried by the bottom section to aid in the folding or setting up operation. 70

In testimony whereof I affix my signature.

ANDY KRONER.

Copies of this patent may be obtained for five cents each, by addressing the "Commissioner of Patents, Washington, D. C."
